COMBINED DISPLAY CASE AND DISPENSER FOR CEREAL BOXES AND THE LIKE

Carl A. Sand, Cincinnati, Ohio, assignor to The Brunkhoff Manufacturing Company, Cincinnati, Ohio, a corporation of Ohio

Application June 26, 1958, Serial No. 51,562

Term of patent 14 years

(Cl. D80—11)

FIG. 1.

FIG. 2.

FIG. 3.

FIG. 4.

Figure 1 is a plan view of a combined display case and dispenser for cereal boxes and the like showing my new design.

I claim:

The ornamental design for a combined display case and dispenser for cereal boxes and the like, substantially as shown.
